CATHODE RAY TUBE

Kurt Schlesinger, Berlin, Germany

Application July 15, 1933, Serial No. 680,583
In Germany July 19, 1932

2 Claims. (Cl. 250—27.5)

It is known that in the case of television images reproduced by gas-filled Braun tubes a light co-ordinate cross on a darker ground is always noticeable within the rectangular image field.

5 This cross results from a decrease in the dissociation of the ions at the moment in which the strength of field between the deflecting plates passes through zero. At this moment the sensitivity of the tube would appear to be somewhat diminished, the rate of deflection retarded, and accordingly the density of light increased in the two axial planes. This effect will be referred to in the following as center point error.

10 It is known that this error in deflection may be overcome by causing the ray always to be curved in the plate space, i. e., by avoiding the point $E_x=0$ entirely.

Fig. 1 illustrates the conditions. The center point of the image field on the luminous screen 20 1 of the cathode ray tube 2 is taken to be the point 3. Normally the one plate 4 is passed together with the anode 5 on common potential to earth, and to the other plate 6 there is passed the potential of the A. C. generator 7, with special 25 form of curve, causing the scanning of the image.

The center point of the image is now distinguished by the fact that in the case thereof the ray runs in a straight line from the anode to the screen, i. e., is not bent. Here the center point error takes 30 place.

Now it is obvious and is known that fundamentally this error may be avoided by the fact that a straight path of the ray is omitted entirely, and the ray enters the plate space in inclined 35 fashion, as indicated by the dotted line 8. In this connection its inclination is such that if it were to proceed in a straight line the same, as shown, would be situated outside of the field of image. In this method, therefore, an additional bias—the battery 9 in Fig. 1—will require 40 to be connected in series with the deflecting potential 7, which deflects the ray to such extent that the same again falls on the center point 3 of the luminous screen when the alternating potential of 7 passes through 9.

45 A method has become known in which the oblique entry of the ray into the plate space is accomplished by the fact that the neck of the tube together with the entire ray-generating system and the anode 5 are furnished with a correspondingly inclined position. This method, however, possesses appreciable disadvantages in the manufacture. The angle of deviation of the neck of the tube must be performed very ac-

curredately. The production of the tubes in machines is very difficult if the tubes do not have straight axes, the application of the plates to a common foot of the system is difficult, etc.

The subject matter of the invention refers to 5 television tubes, which are free from the center point error, and which operate fundamentally with inclined entry of the ray into the plate space, but with the use of special arrangements for the preliminary electrical deflection of the 10 ray are so constructed that the axis of the tube remains straight and the entire system central. Additional subject matter of the invention beyond this is constituted by tubes, in which the 15 dimensioning of the systems for bending the ray is so performed that one single potential, and accordingly one single lead, is sufficient for reliably producing the correct passage of the ray in all bending fields.

The illustration of a simple embodiment of the 20 invention is given in Fig. 2. This system is straight-sighted, but displaced parallel to itself. The ray leaves the anode diaphragm 1 vertically to the plane of the anode. Its normal path would be the axis 2 of the tube to the screen 3, which 25 would strike at its actual center point 4. According, however, to the invention, there is provided behind the anode aperture a peculiarly constructed box system 5, 6 consisting of two 30 angles. The angle 5 of this system is connected 35 up with the same lead as the anode, i. e., in practice to earth. The lead is designated 7, and the connection between 5 and 7 is shown in Fig. 2. The angle 6 of the box system is situated on a 40 bar 8, which possesses a negative potential as compared with the anode bar 1. In consequence the ray will be deflected in space towards the undisturbed axis 2 to the extent of the angle α . The deflection α is of such extent that the ray 45 would now just strike the lower right hand edge 9 of the image if no additional forces were to act on the same. With this critical inclination, the extent of which is adjustable by the potential at 8, the ray enters the actual deflection plate space 10 and 11, of which a frontal view at A—B 45 is shown in Fig. 4. The plate 11, as usual, is conducted outwards (preferably by means of the common foot of the tube at a terminal 12, with which there is connected on the outside the generator 13, which takes care of the line deflection 50 and is always dynamically earthed). Generally speaking, therefore, the plate 11 possesses the potential of the anode bar 1. It is accordingly necessary at the plate 10, which is situated opposite thereto, to apply in turn a potential which is 55

negative in relation to the anode, so that the ray will be bent back into its old axial direction 14 and, although with a certain displacement parallel to itself, will again approach the center 5 point of the luminous screen. According to the invention, the deflection sensitivities of the particular co-ordinates of the box system 5, 6 and the main deflecting system 10, 11, or 15, 16 are selected to be equal to each other. In this case 10 the plate 10 may be connected with the bar 8 in direct fashion, and it is accomplished automatically that the ray again returns to the correct axial position. If the potential at 8 is varied, viz., proceeding from earth potential to a 15 value of approximately -200 volts, there is accordingly not to be observed on the stationary image point 4 anything beyond a slight displacement amounting to perhaps 5-6 mm. in the direction of the one corner of the image. If on 20 the other hand the ray is allowed to pass over the television image screen, there is to be observed upon application of the same measure (variation of the potential 8) that the disturbing light cross of the center point error moves continuously towards one corner of the image, and finally passes beyond the edge of the picture. In this manner the desired effect of rectifying the error has been obtained without varying the 25 sensitiveness of the tube. Merely the image screen has been displaced parallel to itself to the extent of a few millimetres.

This disadvantage may be avoided by using the form of embodiment of the invention illustrated by way of example in Fig. 3, with two 30 bending condensers and bending of the ray on several occasions. In a co-ordinate—the application to the space will be readily understood—there is shown in Fig. 3 the main anode 1 of the tube, followed by a cross-section through a 35 first box system with the plates 2 and 3. The plate 3 is connected with the anode potential bar 4, and the plate 2 on the other hand with a bar having the bending potential 5, i. e., with a potential of, for example, -100 volts, which is 40 somewhat negative as compared with the anode and otherwise is capable of regulation. In consequence the ray traverses a parabola with a deflecting angle α in the same manner as if it had proceeded in a straight line from the center of the 45 plate 7 at the angle in question. According now to the invention, there follows on the system 2, 3 a system 8, 9 of plates, possibly of the same 50 dimensions, but twice as long and having reversed polarity. In view of the doubled ratio

$$\frac{1}{d}$$

it is accordingly possible to accomplish in the 55 system 8, 9 that the ray reverses its direction in relation to the axis of the tube. The same now behaves in such fashion as if it proceeded from a virtual source of emission 10 outside of the tube axis, and by varying the potential at 5 it is possible to accomplish that this virtual source is 60 situated more or less eccentrically to the tube axis. As already stated above, the potential 6 is again adjusted in such fashion that continuation of the new path from 10 in a straight line would be situated just outside the corner of the image. 65 With this inclination the ray enters the actual plate space 11, 12, and if in accordance with the invention the sensitivity of all condenser fields is adjusted to be the same, it may be accomplished 70 by earthing 12 over the deflecting generator 13, 75 and by connection of 11 with 5, that the ray

leaves the entire system with an axis of movement incidental to that axis of the tube, so that upon the adjustment of the bending potential 6 there is no change at all in the position of the center point of the image on the screen, whilst 5 at the same time the error cross departs from the field of image.

Owing to the different distances of the deflecting plates from the anode in the case of series connected condensers, the box condensers must 10 also be spaced differently in the two-co-ordinates, i. e., their cross-sections are not squares, but right angles. Details of this nature, however, do not vary in any way the basic idea of the invention as described, this also applying to an equal extent 15 to the fact that in complicated fashion it is naturally also possible to employ bending systems of different sensitivities if on the other hand for this purpose a corresponding number of different D. C. bending potentials are generated and supplied. It may be particularly pointed out that 20 all results obtained with electrical bending fields may also be accomplished without difficulty with the assistance of magnetic bending fields. It is possible by means of coils placed inclinedly against 25 the image co-ordinates and arranged either inside or outside the tube to produce magnetic transverse fields, which cause the passage of the ray as described, and it is also readily possible, 30 for example by winding and subsequent excitation with the same current, to fulfill the condition that the amounts of the successive bends again result in the direction of the axis.

I claim:

1. Braun tube for television and the like purposes comprising a straight evacuated envelope, a gas-filling inside said envelope, a cathode and an anode arranged in operative relationship thereto for producing a cathode ray, means for concentrating the cathode ray, means for controlling the intensity of the cathode ray, a picture receiving screen, scanning means comprising two pairs of deflecting plates for deflecting to a varying degree the cathode ray in two directions vertical to each other for scanning said picture receiving screen, further deflecting means of constant intensity being independent of said deflecting plates and being mounted between said anode and said deflecting plates for causing the ray to enter the space between said deflecting plates under an angle to said deflecting plates, and still further deflecting means causing the ray to proceed into said picture receiving screen in its original direction after having passed said deflecting plates systems when said scanning means are out 55 of their operative condition.

2. Braun tube for television and the like purposes comprising a straight evacuated envelope, a gas-filling inside said envelope, a cathode and an anode arranged in operative relationship thereto for producing a cathode ray, means for concentrating the cathode ray, means for controlling the intensity of the cathode ray, a picture receiving screen, two pairs of deflecting plates for deflecting the cathode ray in two directions vertical to each other for scanning said picture receiving screen, two further pairs of deflecting plates mounted at right angles to each other between said anode and the first said deflecting plates, and means for connecting one plate of each of said further deflecting plates systems with one plate of one of the first said deflecting plates systems.
